R. C. Hamilton

BY Warren D. House
His ATTORNEY.

UNITED STATES PATENT OFFICE.

LEWIS I. RUTTER, OF KANSAS CITY, MISSOURI.

BALL RACK.

Application filed March 10, 1922. Serial No. 542,583.

To all whom it may concern:

Be it known that I, LEWIS I. RUTTER, a citizen of the United States, residing at Kansas City, in the county of Jackson and 5 State of Missouri, have invented a certain new and useful Improvement in Ball Racks, of which the following is a specification.

My invention relates to improvements in ball racks.

10 It is particularly well adapted for use on bowling alley ball racks.

One of the objects of my invention is to provide novel cushioning means for holding balls apart on the runway of a rack, for 15 the purpose of preventing the balls striking each other so as to splinter or otherwise damage them.

A further object of my invention is to provide cushioning means of the kind described which is simple, cheap to make, durable, not liable to get out of order and which is wholly automatic in operation.

A further object of my invention is to provide a novel ball cushioning device which 25 can be readily applied to ball racks now in use.

The novel features of my invention are hereinafter fully described and claimed.

In the accompanying drawing, which illustrates the preferred embodiment of my 30 invention,

Fig. 1 is a side elevation of a portion of a ball rack provided with my improved cushioning means.

35 Fig. 2 is an enlarged perspective view of one of the yokes and cushioning pad depending therefrom.

Fig. 3 is a cross section on the line 3—3 of Fig. 4.

40 Fig. 4 is an enlarged vertical sectional view, partly broken away, of an end portion of a ball rack provided with my improvement taken on the line 4—4 of Fig. 3.

Similar reference characters designate 45 similar parts in the different views.

1 designates each of two parallel longitudinal runway members of a ball rack, such as is ordinarily employed in bowling alleys. The end of the rack has an inclined portion 2, provided at its lower end, Fig. 1, with a ball stop comprising a vertical board 3, secured at its lower end to and between the members 1. 4 designates the balls used on the runway, having a uniform diameter 55 and adapted to be spaced apart and held from striking each other by my improved

cushioning devices, each of which comprises, preferably, a flexible resilient wedge-shaped cushioning pad 5, preferably of soft rubber, which has its upper thicker end clamped to 60 the transverse portion of an inverted U-shaped yoke 6, by a transverse plate 7, which is secured to the transverse portion of the yoke 6, by bolts 8, having nuts 9.

The pad 5 depends between the arms of 65 the yoke 6 in the path of the balls 4. The lower ends of the arms of the yoke 6, are provided with inwardly extending projections 10, which are respectively secured to the under sides of the members 1 by screws 70 11.

The yokes 6 are spaced apart a distance substantially the same as the diameter of the balls 4, and are disposed in positions such that the pads 5 will be in the path of 75 the balls 4, and will project between the balls below the centers thereof.

In the operation of my invention, the first ball will run on the runway between the yokes 6, and past the pads 5, and will come 80 at rest against the stop 3. The next ball will run down the place of rest portion 2, of the runway and will strike against the last pad 5, to the left, as viewed in Fig. 1, which will bear against the first ball and will hold 85 the two balls apart. In like manner, the balls as they consecutively pass down the runway will respectively come to rest separated from each other by the intervening pads 5.

By having the pads resilient and wedge-shaped, and fastened at their thicker ends, to the yokes, they will have a spring action 90 which will force them from the top of the balls to the rear thereof, as the balls pass under them and come to rest. The pads 5 by preventing the balls contacting with each other, prevent the balls from being marred or damaged as often happens when the balls forcibly strike each other when rolled onto 100 the runway.

It will be noted that the yokes 6 are each disposed to the rear of the division line between the balls. This is for the purpose of 105 enabling the pads 5 to assume their proper protective position between the balls and to prevent each pad from resting on the upper side of the ball just in front of the pad when such ball comes to rest.

I do not limit my invention to the structure shown and described, as many modifications, within the scope of the appended 110

claims, may be made without departing from the spirit of my invention.

What I claim is:—

1. In a ball rack of the kind described, a runway having a place of rest for balls, inverted U-shaped yokes mounted on said runway at said place of rest and spaced apart from each other a distance substantially the same as the diameter of the balls used, and flexible cushioning devices respectively suspended from said yokes in the path of said balls and in position in which they will respectively hold the balls apart when the latter are at said place of rest on the runway, substantially as set forth.
2. In a ball rack of the kind described, a runway having a place of rest for balls, supporting devices mounted on said runway at said place of rest, and wedge-shaped resilient cushioning pads fastened at their thick-

er ends respectively to said devices and arranged to depend between and to hold apart said balls when the latter are at said place of rest on the runway, substantially as set forth.

3. A cushioning device of the kind described comprising an inverted U-shaped yoke having means for being attached to and to bridge over a runway for balls, and a flexible resilient wedge-shaped cushioning pad fastened at its thicker end to the transverse portion of said yoke and depending between the arms of the latter and adapted to extend between and hold apart two balls on the runway, when the yoke is attached in the operative position to the latter, substantially as set forth.

In testimony whereof I have signed my name to this specification.

LEWIS I. RUTTER.
